MAX BLANSHAFT, ROBERT TOW, AND HENRY WETSTEIN, OF NEW YORK, N. Y.

KNOB LOCK FOR POCKETBOOKS AND THE LIKE.

Application filed July 9, 1920. Serial No. 394,873.

To all whom it may concern:

Be it known that we, MAX BLANSHAFT, ROBERT TOW, and HENRY WETSTEIN, citizens of the United States, and residents of Bronx, in the county of Bronx and State of New York, have invented certain new and useful Improvements in Knob Locks for Pocketbooks and the like, of which the following is a specification.

10 The invention pertains to what are termed knob-locks of the character employed on frames for pocket-books, hand-bags and the like, and the invention resides in a new construction of knob-lock and in the method 15 of producing the same from an individual blank. One purpose of the invention is to provide an extremely durable and attractive knob-lock in one integral piece comprising a body portion having securing lugs at its 20 lower edge, a vertical member extending upwardly from said body portion and a knob of suitable outline on the upper end of said vertical member, said vertical member at its upper end being centrally below 25 said knob, which, in accordance with our invention may be either globular or of balloon shape or other suitable configuration. These knob-locks or lock-knobs are used in pairs and secured to the opposite 30 members of the frame of a pocket-book or the like and have an interengaging relation for locking the members of the frame closed together. Lock-knobs or knob-locks for pocket-book frames are generally speaking 35 well known, but as heretofore constructed have a cheap or unattractive appearance, and one object of our invention is to provide extremely durable knob-locks each in one integral piece and of attractive appearance.

40 The invention will be fully understood from the detailed description hereinafter presented, reference being had to the accompanying drawings, in which:

45 Fig. 1 is a front elevation, partly broken away and partly in section, of a handbag frame equipped with the knob-locks of our invention;

50 Fig. 2 is a perspective view of the metal blank from which the knob-lock of our invention is constructed;

55 Fig. 3 is a side elevation of the same after the upper portion of the blank has passed through the first step of the process looking to the formation of the spherical knob;

Fig. 4 is an edge view, taken from the right hand side of Fig. 3, of the same;

Fig. 5 is a side elevation of our knob-lock in its completed condition and as transformed from the state in which the blank 60 is illustrated in Fig. 3;

Fig. 6 is an edge view, taken from the right hand side of Fig. 5, of the same;

Fig. 7 is a side elevation of a modified 65 form of metal blank adapted to the production of our knob-lock, the modification residing wholly in the shape of the lower or body portion of the blank, the blank otherwise being the same as the blank shown in Fig. 2 and intended for the treatment 70 represented in Figs. 3 to 6 inclusive;

Fig. 8 is a further modified form of blank with which our invention may be carried 75 into effect, the modification residing in a slight change in the upper portion of the blank, from that shown in Fig. 2, whereby an approximately balloon shape knob may be produced instead of the spherical knob shown in Figs. 5 and 6;

Fig. 9 is a side view of the knob-lock element as produced from the blank shown in Fig. 8, and

Fig. 10 is an edge view, partly broken away, of the handbag frame members 80 equipped with the knob-locks of our invention.

In the drawings, 10 indicates a portion of a handbag equipped with frame members 11, 12 of ordinary type, said members being 85 hinged together at 13, as usual, and equipped with a pair of knob-locks 14, 15 embodying our invention and adapted to be sprung into interlocking engagement in a customary manner and as illustrated in Figs. 1 and 10. The knob-locks 14, 15 are alike in construction and are produced from the blank shown in Fig. 2 and in accordance with the method of manufacture indicated in Figs. 2 to 5 inclusive.

The blank shown in Fig. 2 comprises a body portion 16 having on its lower edge integral lugs 17 and at one end a vertical member or stem 18 at whose upper end is formed a head 19 which is initially flat and of foliate outline, said head being integral 100 with said stem 18 and comprising a series of substantially corresponding equal sided leaves 20 whose edges are curved on diverging lines and intersect one another and which leaves radiate from the middle or 105

body portion 21 of the head 19, which body portion is solid and finally becomes the top and sides of the finished knob, which we number 22.

5 The first step in the formation of the spherical knob 22 from the blank shown in Fig. 2 is the folding downwardly of the leaves 20 and adjacent portions of the body 21 on corresponding vertical lines or to the 10 position in which the blank is shown in Figs. 4 and 5, in which the head 19 of the blank, having been transformed into a head of different shape, we number the head 23 in Figs. 3 and 4. It may be observed on 15 reference to Figs. 3 and 4 that the head 23 is open at its lower end and at said end has a serrated edge created by the leaves 20 and that the head 23 is supported by the stem 18 and wholly overhangs said stem at one face 20 thereof. In Figs. 3 and 4 we number the leaves of the head 23 correspondingly with the leaves 20 of Fig. 2. The top of the head 23 is convexed upwardly.

After the blank has been transformed into 25 the condition shown in Figs. 3 and 4, said blank is further subjected to dies which close in the leaves 20 into intimate relation and throw the sides and top of the head 23, as well as the leaves 20, into a spherical form 30 or knob 22, shown in Figs. 5 and 6, and at the same time the head portion of the blank, while being transformed into the knob 22, is displaced laterally so that the stem 18 becomes located at the center of the lower 35 side or bottom of the knob 22, as shown in Fig. 6, thereby producing a structure which is of symmetrical and attractive appearance, as distinguished from the structure shown in Fig. 4. In the transformation of the head 19, shown in Fig. 2, to the spherical knob 22, shown in Fig. 6, we do not alter the formation of the body portion 16 of the blank. The locking member when reduced to the construction shown in Figs. 5 and 6, 40 is complete and ready for application to the frame-members 11, 12. In securing the locking members or knob-locks to the frame members 11, 12, the lugs 17 are inserted downwardly through openings in the upper 45 edges of said frame members and headed or upset, as indicated in Fig. 1, within said frame members, thereby securing the locking features to the bag-frame.

In Fig. 7 the modification resides wholly 50 in presenting a different formation of body portion to the blank, and we will therefore number the stem and head of the frame shown in Fig. 7 correspondingly with the numbering used on Fig. 2, and the body portion of the blank in Fig. 7 we number 24. The body portion 24 instead of being extended all to one side of the stem 18, extends laterally on both sides of the lower end 55 of said stem, as shown, and is formed with the securing lugs 25 corresponding with the

6 lugs 17 of Fig. 2, one lug 25 being at each side of the vertical plane of the stem 18, this being a desirable construction in adding 10 stability to the knob-lock and presenting some advantages in construction over having the stem 18 at one extreme end of the body 16. We present Fig. 7 to indicate that our invention does not reside particularly in the outline of the body portion 16 of the blank and that said body portion may be 15 modified in outline within the scope of our invention.

In Fig. 8 we illustrate a further form of blank with which our invention may be carried into effect in producing an approximately balloon-shaped knob 26, shown in Fig. 9, as distinguished from the spherical knob 22, shown in Figs. 5 and 6. The blank shown in Fig. 8 comprises a body portion 27 corresponding with the body portion 16 of Fig. 2, and having on its lower edge securing lugs 28 and at one end a vertical neck or stem 29 on whose upper end is a foliate head 30 comprising leaves 31 radiating from a solid body 32. The head 30 corresponds exactly with the head 19 of Fig. 2, with the exception that the leaves 31 of the head 30 are somewhat longer than the leaves 20 of Fig. 2, so that in the formation of the final knob, said knob will take the outline 95 shown in Fig. 9 instead of that shown in Fig. 6. The transformation of the head 30 into the knob 26 corresponds with the steps represented in Figs. 2 to 6 inclusive, and therefore no further description of the same 100 is needed. The invention is carried out with the blank shown in Fig. 8 just the same as with the blank shown in Fig. 2. In Fig. 8, however, we modify the shape of the leaves of the head of the blank so as to produce the modified form of knob 26.

The knob-lock of our invention is of very durable character and attractive in appearance and produced by a method which we have invented with a view of facilitating 110 the manufacture of an attractive knob-lock having to all appearances a solid head, from one integral blank.

What we claim as our invention and desire to secure by Letters Patent, is

1. A knob locking device for attachment to the frames of handbags and the like in one integral piece of sheet metal comprising a lower body portion having securing lugs on its lower edge and an upwardly projecting stem formed on its upper end with a knob having an upper body portion and leaf sections at the edges thereof folded together in edge to edge relation and completing and closing the surfaces of said knob, one of said leaf sections being integral with the upper end of said stem.
2. A knob locking device for attachment to the frames of handbags and the like in one integral piece of sheet metal comprising

a lower body portion having securing lugs on its lower edge and an upwardly projecting stem formed on its upper end with a knob having an upper body portion and leaf sections at the edges thereof folded together in edge to edge relation and completing and closing the surfaces of said knob, said knob at its lower side having its central portion on the upper end of said stem, whereby said knob overhangs said stem on all sides thereof.

3. The method hereinbefore described of manufacturing a knob locking device for the frames of handbags and the like, consisting in forming a sheet metal blank having an elongated body portion, lugs on the lower edge thereof, a stem projecting upwardly

therefrom and a foliate head on the upper end of said stem composed of a middle solid body portion and substantially corresponding leaves projecting from the edges thereof and adjoining one another in series at the inner edges of the sides thereof, and shaping said head and closing said leaves together in edge to edge relation to form a closed knob on and overhanging all sides of the upper end of said stem.

Signed at New York city, in the county of Kings and State of New York, this 7th day of July, A. D. 1920.

MAX BLANSHAFT.
ROBERT TOW.
HENRY WETSTEIN.
